(57) CLAIM

The ornamental design for a dog toy as shown and described.

DESCRIPTION

FIG. 1 is a front right perspective view of a dog toy showing the design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof;

FIG. 7 is a top plan view thereof; and,

FIG. 8 is a cross-sectional view thereof, taken along line 8-8 of FIG. 2.

The broken lines in the drawings depict portions of the dog toy and form no part of the claimed design.

1 Claim, 6 Drawing Sheets
